MAGNETICALLY ACTUATED ANNUNCIATOR FOR ELEVATORS

Filed Nov. 29, 1952

UNITED STATES PATENT OFFICE

2,680,242

MAGNETICALLY ACTUATED ANNUNCIATOR
FOR ELEVATORS

Carl John Drathschmidt, New York, N. Y.

Application November 29, 1952, Serial No. 323,280

7 Claims. (Cl. 340—372)

1

This invention relates to annunciators and more particularly to a magnetically actuated annunciator.

It is an object of the present invention to provide an annunciator which does not work by gravity and which contains no hinges which would wear out after prolonged use.

It is another object of the present invention to provide an annunciator of the above type which can be used vertically or horizontally.

It is still another object of the present invention to provide an annunciator of the above type which can be conveniently located near the control handle in an elevator thus permitting the operator to observe the same without bending his head from its normal position.

It is still another object of the present invention to provide an annunciator of the above type which is small and compact and which contains practically no parts which can wear out.

It is still another object of the present invention to provide signalling indicia which are actuated by an electric magnet, a permanent magnet being provided at the center of the electric magnet and serving to retain the actuated indicia in operative position after the electric magnet has been de-energized, this permanent magnet being insulated on its side remote from its associated indicia so as to not interfere with the adjacent indicia of the next electro-magnet.

Other objects of the invention are to provide an annunciator bearing the above objects in mind which is of simple construction, inexpensive to manufacture, has a minimum number of parts, is compact, easy to operate and efficient in use.

For other objects and for a better understanding of the invention, reference may be had to the following detailed description taken in connection with the accompanying drawing, in which:

Fig. 1 is a perspective view of an annunciator embodying the features of the present invention;

Fig. 2 is an exploded, perspective view of the principal parts of the present invention;

Fig. 3 is a vertical sectional view taken along line 3—3 of Fig. 2;

Fig. 4 is a vertical sectional view taken along line 4—4 of Fig. 2;

Fig. 5 is a view similar to Fig. 4 but showing the sliding tab in a returned position and

Fig. 6 is a front elevational view of one of the electro-magnets shown alone and showing the permanent magnet and the insulator therefore.

Referring more in detail to the drawing, in 55

2

which similar reference characters designate corresponding parts throughout the several views, there is shown an annunciator, referred to collectively as 10, and including a rear casing 11 having a bottom wall 12 and a rearwardly inclined back wall 13, substantially as illustrated.

A front casing 14 having a rearwardly inclined front wall 15 parallel to rear wall 13 is provided therein with a window opening 16, substantially as illustrated, the window opening 16 overlying the back wall 13.

The front wall 15 is integrally formed with rearwardly extending, vertical side walls 17, a top wall 18 and a rear wall 19, the rear casing 13 fitting within the front casing 14 in the manner shown in Figs. 1 and 3 with the rear wall of casing 13 being secured to the rear wall of casing 14 by means of a vertically extending extension 20 of rearwardly inclined back wall 13 and screws 21. A vertically extending extension 22 of front wall 15 of front casing 14 is further secured to bottom wall 12 of rear casing 11 by means of brackets 22^a and screws 23, as shown in Fig. 3. The front casing 14 may be removed from rear casing 11 by removal of screws 21 and 23, thereby permitting access to the interior parts to be described.

A plurality of magnetic actuators, referred to collectively as 24, are secured to back wall 13 in longitudinally and vertically spaced positions below the window opening 16, substantially as illustrated.

All of these actuators 24 are identical in construction and but one of them will therefore be described in detail.

Each actuator 24 includes a core 25 around which is coiled copper wires 26, the free ends of wire 26 being connected to terminal screws 27 mounted in a front board 28 of plastic suitably secured to bottom wall 12 and to insulated cord 29 suitably connected to a source of voltage. Each of the wires 26 is connected in parallel with the source of voltage, not shown, and in series with the manually operable switches on each floor by means of the terminal screws 27. A buzzer 30 is also connected in series with the source of voltage so that when any one of the manually operable switches, not shown, is closed to actuate one of the cores 25, the elevator operator will be advised by sound as well as visually in a manner to be hereinafter described.

The core 25 is hollow at its center and mounted upon an inner core 31 of suitable material secured at its bottom to rear wall 13 by means of screws 32, as shown in Fig. 3. The inner core

31 is hollow at its center and receives therewithin a permanent magnet 33, the magnet 33 being secured in place by means of set-screws 34. It will be noted that the permanent magnet 33 extends upwardly beyond the inner core 31 and core 25 for a purpose to be hereinafter described.

An elongated brass plate 35 having a bottom 36 and vertically extending, longitudinal side walls 37 and 38 is suitably secured within the window opening 16 along the upper edges of side walls 37 and 38, as shown in Fig. 3, the bottom 36 being provided with a plurality of openings adapted to receive the upwardly extending permanent magnets 33. The plate 35 is integrally formed with transverse end portions 39 and 40 of greater thickness than the bottom 36 and a central, longitudinal portion 41 connecting the transverse portions 39 and 40 and also of a greater thickness than the bottom 36, the portions 39, 40 and 41 providing a pair of longitudinal recesses 42 and 43 adapted to slidably receive a plurality of sliding tabs 44, substantially as illustrated. The tabs 44 are colored black for a purpose to be hereinafter described, and are formed of steel or iron so as to be permeable to the magnetic field of electro-magnetic actuators 24.

The bottom 36, the transverse portions 39 and 40 and the longitudinal portion 41 are provided with a longitudinally extending slot which slidably receives an elongated bar 45 extending outwardly of the casing 14 at one side and having secured to its end a handle 46. The bar 45 is formed with a vertically extending flange 47 which slides in a vertical slot provided in the portions 39, 40 and 41 above the bar 45, substantially as illustrated.

As shown in Fig. 2, each of the tabs is normally positioned in recesses 42 and 43 to the left of its respective electro-magnetic actuator 24, the extreme leftward movement of these tabs being limited by the transverse portion 39 and pins 48 secured to the upper face of bottom 36. During the energization of the cores 25 upon the closing of the manually operable switches in each floor, the magnetic flux emanating therefrom draws the associated tab 44 from its extreme leftward position described above to a position adjacent the permanent magnet 33, where it is retained by the latter after the core 25 has been de-energized, see Fig. 4. This permanent magnet effect is very important, as it prevents the tab from being drawn away from the de-energized actuator 24 when an adjacent actuator is energized to the left.

The permanent magnets 33, on their faces remote from their associated tabs 44, are cut away at their top ends and brass insulators 49 inserted therein, substantially as illustrated. These insulators 49 prevent the permanent magnets 33 from retaining a rightwardly disposed tab 44 from responding to its associated actuator 24 and are an important feature of the present invention.

A transparent glass 50 closes the window opening 16 and has marked thereon gold numerals adapted to overlie the sliding tabs 44, substantially as illustrated in Figs. 1 and 2. When the tabs 44 are in the extreme left position shown in Fig. 2, the gold numerals are seen against the gold background of bar 35 and are therefore substantially invisible. However, upon movement of one of the tabs 44 to its position adjacent its respective permanent magnet 33 in response to the closing of one of the manually operable

switches, not shown, on one of the floors and the actuation of its respective core 25, the gold numerals will be seen against the background of the black colored tab, thereby making the numeral clearly visible, gold on black. This visibility of a particular numeral will be accompanied by the actuation of the buzzer 30 in accordance with the circuit already described. The numeral thus made visible will, of course, correspond to the particular floor on which the switch has been closed.

When the operator desires to clear the annunciator, it is only necessary to push the bar 33 by means of handle 46 to the extreme left position shown in Fig. 5, pins 51 secured to bar 45 and appropriately spaced carrying the tabs back to their respective inoperative positions limited by the pins 48. The handle 46 and bar 45 are then returned by spring S to their original position to permit the tabs 44 to respond to the energization of their respective actuators 24.

While I have shown the tabs 44 as moving in a horizontal direction under the influence of the actuators 24, it will be readily apparent that they may be equally arranged in a vertically movable path without materially altering the arrangement and construction, since their movement depends not on gravity but upon the actuation of their respective electro-magnets, and that they are retained in the operative position by the permanent magnets 33.

It will be noted that an important feature of the present invention is the provision of the above mentioned permanent magnets, inasmuch as they retain the tabs 44 in the operative position behind the gold numerals and thereby prevent them from being drawn back to their inoperative position by the actuation of an adjacent actuator 24, even though the actuator to which they originally responded is no longer actuated. Another important feature of the present invention is the provision of the brass insulators 49 on the other side of the permanent magnets 33, thus preventing the magnets 33 from retarding the response of a rightwardly disposed tab 44 in response to its respective actuator 24.

While various changes may be made in the detailed construction, it shall be understood that such changes shall be within the spirit and scope of the invention as defined by the appended claims:

Having thus set forth and disclosed the nature of my invention, what is claimed is:

1. An annunciator comprising a transparent glass carrying colored indicia thereon, a channel-shaped member disposed below said glass in alignment with said indicia, the color of said channel-shaped member being substantially the same as that of said indicia, a plurality of contrastingly colored tabs disposed on said channel-shaped member and adapted to slide into and out of vertical alignment with said indicia, a plurality of electro-magnets disposed below each of said slideable tabs, said tabs being formed of a magnetic permeable material and adapted to slide into alignment with said indicia upon actuation of said electro-magnets, a permanent magnet associated with each of said electro-magnets and adapted to retain said tabs in said aligned positions upon deenergization of said electro-magnets, and means for manually returning said tabs to their visually inoperative positions against the action of said permanent magnets.

2. An annunciator according to claim 1, each of said permanent magnets on its side remote

from its corresponding tab having a shield of magnetically impermeable material.

3. An annunciator according to claim 1, each of said electro-magnets being connected in parallel with a source of voltage and connected in series with a manually operable switch, the nature of the indicia disposed over each electro-magnet corresponding to the location of its respective switch.

4. An annunciator according to claim 3, a sounding means being connected in series with the source of voltage and adapted to sound upon actuation of any one of said electro-magnets.

5. An annunciator according to claim 1, said means for manually returning said tabs to their visually inoperative positions against the action of said permanent magnets comprising a rod, said channel-shaped member being adapted to slidably receive said rod below said tabs and a plurality of upwardly extending pins carried by said rod and adapted to return all of said tabs to their inoperative positions upon displacement manually of said rod.

6. An annunciator comprising a hollow housing having an opening in the front thereof, a transparent glass disposed in said window and carrying indicia thereon, a plurality of channels disposed within said housing below said window and glass, the color of said channels being substantially the same as that of said indicia, a plurality of flat tabs disposed slidably within said channels and below said indicia, said tabs being colored so as to contrast with said indicia and being adapted to slide into and out of vertical alignment with their respective indicia, a plurality of electro-magnets disposed within said housing below said channels and adapted to each underlie one of said tabs, each of said tabs being formed of magnetically permeable material and adapted to slide into alignment with its particular indicia upon actuation of its particular electro-magnet, a permanent magnet associated with each of said electro-magnets and adapted to retain its tab in the visually operative position upon de-energization of its particular electro-

10
5 magnet, each of said permanent magnets on its side remote from its respective tab having a shield of magnetically impermeable material, means for supplying voltage to said electro-magnets, each of said electro-magnets being connected in series with a manually operable switch, the nature of the indicia disposed over each electro-magnet and its respective tab corresponding to the location of its respective switch, sounding means connected in series with said voltage supplying means and adapted to sound upon actuation of any one of said electro-magnets, a rod, said channels being adapted to slidably receive said rod below said tabs, and a plurality of upwardly extending pins carried by said rod and adapted to return all of said tabs to their inoperative positions upon manual displacement of said rod.

20
15 7. An annunciator comprising a transparent plate carrying indicia thereon, a second plate disposed below said transparent plate in alignment with said indicia, the color of said second plate being substantially the same as that of said indicia, a plurality of contrasting colored tabs 25 of magnetically permeable material disposed on said second plate and adapted to slide into and out of vertical alignment with said indicia, a plurality of electro-magnets disposed below each of said slidable tabs, said tabs being adapted to slide 30 into alignment with said indicia upon actuation of said electro-magnets, a permanent magnet associated with each of said electro-magnets and adapted to retain said tabs in said aligned positions upon de-energization of said electro-magnets, and means for manually returning said tabs 35 to their visually inoperative positions against the action of said permanent magnets.
